UNITED STATES PATENT OFFICE.

LEO WOERNER, OF ST. LOUIS, MISSOURI.

BAFFLE FOR WATER-TUBE BOILERS.

No. 911,281.

Specification of Letters Patent.

Patented Feb. 2, 1909.

Application filed March 11, 1908. Serial No. 420,342.

To all whom it may concern:

Be it known that I, LEO WOERNER, a citizen of the United States, residing at St. Louis, in the State of Missouri, have invented a certain new and useful Baffle for Water-Tube Boilers, of which the following is such a full, clear, and exact description as will enable any one skilled in the art to which it appertains to make and use the same, reference being had to the accompanying drawings, forming part of this specification.

My invention relates to that form of baffle for water tube boilers which is applied to the lower and also sometimes to the upper tier of water tubes to protect the tubes from the direct heat of the furnace and also to guide the flow of heated gases among the tubes.

One object of my invention is to so construct the members of which the baffle is formed that the baffle will be lighter in weight than those heretofore in general use, so as to obviate the liability of springing the tubes, and also to so construct the members that any individual member can be readily placed in position or removed without removing the adjacent members.

Another object of my invention is to so construct the members that the baffle may be made to extend throughout the entire length of the tier of tubes and at the same time to properly direct the flow of gases among the tubes.

In the accompanying drawings which illustrate one form of baffle made in accordance with my invention, together with a portion of water tube boiler to which the same is applied, Figure 1 is a vertical longitudinal section through the boiler and furnace; Fig. 2 is an enlarged cross section of a portion of the tubes and Fig. 3 is a top plan view.

Like marks of reference refer to similar parts in the several views in the drawings.

5 represents the front wall, 6 the rear wall and 7 the fire wall of the furnace.

8 is the fuel chamber and 9 the combustion chamber, the former being situated between the walls 5 and 7 and the latter between the walls 6 and 7.

50 Resting upon the front and rear walls 5 and 6 are the front and rear water legs 10 and 11, respectively, of the boiler. Extending between the water legs 10 and 11 are the usual water tubes 12. Applied to the upper and lower tiers of the tubes 12 are the baffles

13. These baffles 13 are each composed of two forms of tile members 14 and 15. The tile members 14 are substantially semi-cylindrical in form so as to fit around the tubes 12 in pairs, as best shown in Fig. 2. The lower edges 16 of each pair are in contact, as best shown in this figure, while the upper edges 17 are separated so as to allow of the partial rotation of one of the members around the tube without disturbing the position of the other member. Each of the members 14 is provided with a laterally extending rib 18 which is arranged somewhat above the center of the member and extends throughout the entire length of the member. 60 These ribs 18 are so proportioned that each bears against the corresponding rib of the adjacent member and so locks the parts of the baffle in position around the tubes 12. The members 15 differ from the members 14 65 only in being provided with a rib 19 which instead of extending along the entire length of the member only extends through a very short portion of the length. The ribs 19 lock the members 15 in position in the same 70 manner as the ribs 18 lock the members 14. Each of the members 14 and 15 is provided, 75 preferably just below the rib or projection 18 or 19, with an opening 20 for the insertion of a suitable tool for the rotation of the 80 member.

The baffle 13 upon the lower tier of tubes has its forward end extending over the grate chamber 8 composed of the members 14, while a portion of the rear end over the 90 combustion chamber 9 is composed of the members 15. The entire length of the tubes is thus protected and the products of combustion are prevented from passing up through the forward end of the tubes but 95 are allowed to pass up between the tubes at the rear end. In the upper baffle 13 the position of the members 15 is reversed, being placed at the forward end of the tier of tubes in place of at the rear end. When 100 it is desired to remove one of the members it is rotated partially about the tube, as shown at the central portion of Fig. 2, and the adjacent pair of members are thus freed so that they may be rotated around the 105 tubes and removed.

It will be seen that with my form of baffle the members are comparatively light in weight and not liable to bend the tubes, and that the entire length of the tubes is 110

protected and at the same time the products of combustion are properly guided between the various tubes.

Having fully described my invention, 5 what I claim as new and desire to secure by Letters Patent of the United States, is:

1. The combination with water tubes for boilers, of a baffle for said tubes composed of members the bodies of which are substantially semi-cylindrical, each member being provided with an integral laterally extending rib, each rib having a convex surface and being adapted to engage with the rib of an adjacent member to lock said members in position around the tubes, said members being movable around the tubes to disengage said ribs.

2. The combination with water tubes for boilers, of a baffle for said tubes composed 20 of members the bodies of which are substantially semi-cylindrical, each member being provided with an integral laterally extending rib forming with the body an offset or shoulder, each rib having a convex surface and being adapted to engage with the rib of an adjacent member to lock said members in position around the tubes, said members being movable around the tubes to disengage said ribs.

3. The combination with water tubes for boilers, of a baffle for said tubes composed 25 of members the bodies of which are substan-

tially semi-cylindrical, the bodies of each of said members being of substantially uniform thickness throughout, each member being provided with an integral laterally extending rib, each rib having a convex surface and being adapted to engage with the rib of an adjacent member to lock said members in position around the tubes, said members being movable around the tubes to disengage said ribs.

4. The combination with water tubes for boilers, of a baffle for said tubes composed 35 of members the bodies of which are substantially semi-cylindrical, the bodies of each of said members being of substantially uniform thickness throughout, each member being provided at a point intermediate its edges with an integral laterally extending rib, each rib having a convex surface and being adapted to engage with the rib of an adjacent member to lock said members in position around the tubes, said members being movable around the tubes to disengage 40 said ribs.

In testimony whereof I have hereunto set my hand and affixed my seal in the presence of the two subscribing witnesses.

LEO WOERNER. [L. s.]
